UNITED STATES PATENT OFFICE

WILLIAM J. WHEELER, OF CONESVILLE, OHIO

HOUSEHOLD LOCKER

Application filed June 21, 1930. Serial No. 462,812.

This invention relates to a household appliance which may be conveniently and generally designated as a locker, and it has more particular reference to a receptacle primarily designed for out-of-doors use, the same being mechanically fashioned to provide a combination milk bottle holder and letterbox.

Briefly stated, the structural novelty is predicated upon a suitably proportioned and shaped box having a single door for closing upper and lower compartments, the upper compartment constituting a receptacle for mail, and the lower compartment serving as a holder or closet for one or more milk bottles.

The principal feature of the invention is the retaining device for the door which embodies a latch controlled by means operable from within the house.

A special feature of recommendation in this retaining device is the specific construction of a peculiarly designed latch which has a portion for co-operation with a keeper bracket on the door, and a leg portion which is so located as to literally "kick" the door open when it is unlatched.

In carrying the inventive conception into practice, I have employed an assembly of mechanical details which are mutually related in such a manner as to form a simple and economical combination receptacle and dependable retaining means which is operable only from the back of the box and preferably through the medium of an extension operating rod made accessible for easy manipulation inside the house.

Other objects, features, and advantages of the invention will become more readily apparent from the following description and drawings.

In the drawings:

Figure 1 is a perspective view of a device constructed in accordance with the present invention.

Figure 2 is a front view with the door open to disclose the retaining latch on the interior.

Figure 3 is a horizontal section on the line 3-3 of Figure 2.

Figure 4 is a vertical section on the line 50 4-4 of Figure 2.

Figures 5 and 6 are detail views of the latch and keeper sections.

The device is preferably installed on an interior wall 7 of the building shown in Figure 4 and operated from the interior wall 8. As shown in Figure 1, the numeral 9 designates a vertically elongated somewhat rectangular box whose upper end is formed with an inclined watershedding roof 10. At the extreme top is a letter slot 11 and a hingedly mounted cover plate 12 therefor. The numeral 13 merely designates a spring clip on the outside for holding papers, packages and the like.

The numeral 14 represents the hingedly mounted door having a suitable operating knob 15. On the interior of this door is an arcuate keeper bracket 16 of the configuration represented in Figure 6. As before implied the numeral 17 designates a horizontal partition plate appropriately located on the interior to divide the box into an upper letter receptacle 18 and a lower partition 19 constituting a holder or closet for reception of a milk bottle 20.

The device is primarily designed for holding a full bottle of milk to guard against removal by unauthorized persons. The one door 14 serves as a single closure for both compartments 18 and 19. In the compartment 19 and near the top is a suitably shaped sheath 21 forming a housing for the retaining or fastening means broadly. Rockably mounted on the pivot shaft or pin 22 therein is a specially designed fixture 23. This is in the form of a single casting and includes an arm 24 terminating in a retention nose or detent 25 which is releasably engageable with the keeper bracket 16.

The numeral 26 designates a finger which forms a crotch for reception of the bent end 27 of the operating wire or rod 28. This rod extends through a suitable guide opening in the walls 7 and 8 of the interior where it is provided with a finger knob 28 and a wear plate 29. This rod is of the push-pull variety and if desired may include a return spring 30.

The numeral 31 designates a curvate door opening element. When the door is closed

as shown in Figure 4, the detent 25 of the latch drops into the aperture in the curvate end portion of the keeper bracket 16, thus holding the door 14 closed. In order to open 5 the door, it is necessary to grasp the knob 28^a on the operating rod 28 and pull it inwardly. This rocks the latch on the pivot pin 22 and disengages it from the brackets and at the same time pushes the door opening 10 element 31 against the door to provide momentum or to produce a pitch which throws the door slightly open so that the latch will not drop back and catch in the keeper again.

Thus, the person on the inside of the house 15 disengages the latch and moves the door slightly open so that upon walking on the outside the knob 15 can be grasped and the door moved to full open position as shown in Figure 2 to facilitate insertion or removal of 20 the milk bottle. This also uncovers the front of the letter compartment as is obvious.

It is thought that persons skilled in the art 25 to which the invention relates will be able to obtain a clear understanding of the invention after considering the description in connection with the drawings. Therefore, a more lengthy description is regarded as unnecessary.

Minor changes in shape, size, and rearrangement of details coming within the field 30 of invention claimed may be resorted to in actual practice if desired.

I claim:

A latch device for a barrier having a keeper 35 member thereon comprising a substantially U-shaped member having a pivot pin receiving opening in its bight with its lower leg longer than its upper leg and said upper leg having a depending keeper engaging projection on its free end, and an arm connected with the bight part and extending over the upper leg and spaced therefrom to form a space for receiving an operating member, whereby when the latch member is moved to 40 releasing position the projection will leave the keeper member and an end of the long lower limb will engage the barrier to move the same to open position.

In testimony whereof I affix my signature.
50 WILLIAM J. WHEELER.
